UNITED STATES PATENT OFFICE.

SAMUEL BROD, OF NEW YORK, N. Y.

COMBINED LETTER-SHEET AND ENVELOP.

1,290,891.

Specification of Letters Patent. Patented Jan. 14, 1919.

Application filed February 25, 1918. Serial No. 218,922.

To all whom it may concern:

Be it known that I, SAMUEL BROD, a citizen of the United States, and resident of the city of New York, in the county of New York and State of New York, have invented certain new and useful Improvements in Combined Letter-Sheets and Envelops, of which the following is a specification.

This invention relates to combined envelopes and letter sheets and especially to that type which may be opened by the addressee in the same manner as ordinary envelopes.

The object of this invention is the provision of a letter sheet which may readily be folded and sealed into an envelop without the expenditure of labor greater than that required to fold and insert an ordinary letter sheet into an envelop and to seal the envelop.

A further object of this invention is the provision of a combined letter sheet and envelop which saves paper over the separate sheet and envelop and which is inexpensive to manufacture.

A further object of this invention is the provision of a combined letter sheet and envelop in which the contents or writing cannot be tampered with without destroying the envelop or mutilating the sheet.

A still further object of this invention is the provision of a combined letter sheet and envelop which can be inserted into the typewriter as readily as an ordinary sheet, and on which the address need be written only once.

For the accomplishment of the aforesaid objects, I employ the construction shown in the accompanying drawings, in which—

Figure 1 is a view of that surface of the letter sheet upon which the writing is to be done, as it appears when ready to be folded into an envelop.

Fig. 2 is a rear view of the folded and sealed envelop and Fig. 3 is a front view of the same inverted.

Figs. 4 and 5 show two of the steps necessary to fold the sheet into an envelop.

In the practical embodiment of my invention, I employ the letter sheet 1, which may be of any of the sizes in ordinary use for commercial or social correspondence, and which is included between lines 16, 13 and 17. Said sheet 1 is provided with a seal flap 3 and side flaps 2 integral therewith. While

the shape of seal flap 3 shown is that used in ordinary commercial correspondence, it will be seen from what follows that said flap may be of any of the shapes used in correspondence of any nature without departing from the spirit of my invention.

Seal flap 3 is large enough so that the addressee's name and address may be written thereon, the upper part of said seal flap being covered by a strip of gum 6, made wider at the center than at any other point, as shown at 7. A score 16 in sheet 1 defines the lower edge of the seal flap, which is adapted to fold about said score 16 so that the name and address of the addressee register with and show through window 4 which is cut in the upper part of sheet 1 and which is covered by transparent patch 5.

It is obvious that the window and patch in sheet 1 may be omitted and the address written on the face of the envelop, if desired, instead of on the seal flap.

Side flaps 2 are designed to fold about scores 13 continuous with the longitudinal edges of sheet 1, into the position shown by the dotted lines in Fig. 1 to the rear of the sheet, so that said sheet 1 may be inserted into the typewriter and treated as is the letter sheet now in general use. Said flaps 2 are cut away at 8 to allow the gummed portion of seal flap 3 at its center 7 to be pasted on to the body of the folded sheet 1 as is shown in Fig. 2. The shape of said flaps 2, in general, is such that when folded into their final position in the envelop, they will clear the window 4 (Fig. 2). When no window is used, flaps 2 may be made substantially in outline quadrants of circles.

Transverse score 10 is impressed on sheet 1 between the bottom corners of flaps 2 and defines the bottom edge of folded envelop 14. Additional transverse scores 9 and 11 are made in sheet 1 and serve to indicate the place where said sheet is to be folded and to make easier the folding thereof to the positions shown in Figs. 4 and 5. The distances between scores 10 and 9, 9 and 11, and 11 and edge 17 are all the same and are equal preferably to the distance from score 10 up to the bottom edge of patch 5, when the window is used.

If no window is used, edge 17 of sheet 1 may be brought as close to score 16 as may be desired, the place where the fold occurs being scored as at 9, the additional scores 11

and 10 being positioned suitably for making easy a second fold in the sheet. It can readily be seen that for a bill or a short letter sheet, that portion of the sheet 1 below score 5 9 may be omitted entirely without affecting the final folded envelop.

Longitudinal scores 12 in sheet 1 define the lateral edges of folded envelop 14, and on their distance from the longitudinal 10 edges of sheet 1 depends the size of the portion of flap 2 which projects beyond the sheet proper. When it is desired that the flaps 2 be small, scores 12 are placed close together, but where a large envelop is wanted, the distance between scores 12 must be increased.

My new product is used as follows:

The sheet arriving at the consumer's with flaps 2 folded back out of the way, looks 20 like the ordinary letter sheet excepting for the seal flap, scores and window. The sheet is written on in the typewriter or by hand, addressed on the seal flap as shown in Fig. 1, and is ready for folding into an envelop. 25 Edge 17 is brought up to the bottom edge of patch 5, a fold being made on score 9 (Fig. 4). Score 11 is now registered directly above score 10 and the second fold may then be made, thereby forming one edge 30 of the envelop along score 10. Portions 15 between scores 12 and the edges of sheet 1 are, by this means, folded together with the remainder of the sheet and are now ready to be folded together with flap 2. Said flaps 35 and portions 15 are folded on scores 12 (Fig. 5) and the seal flap 3 then pasted on to the said side flaps and that part of the sheet exposed by the cut-away parts 8 of the side flaps, thereby completing the envelop.

40 It will be seen that the labor of folding the sheet is little, if any, more than that involved in folding the ordinary letter sheet, inserting it into the ordinary envelop and sealing the envelop. A large part of the 45 paper required for making an envelop is dispensed with, printing labor is saved in view of the ease in printing both sides of my improved product, and it will be seen that the postmark appears on the back of the sheet 50 after mailing.

Two or more thicknesses of material are presented everywhere except on the curved parts of the side flaps, which are not greatly exposed to injury, whereby a strong envelop 55 is produced. The letter can not be tampered with without destroying the envelop and sheet, since the folded portions 15 prevent the sheet proper from being drawn out from under the side flaps 2 after folding thereof.

60 To open the folded envelop, the seal flap

is cut along score 16 and removed, or opened or destroyed in the same manner as is that of the ordinary envelop, without any injury being caused to the contents of the letter. While the central portion 7 of gum strip 6 65 is attached to the sheet 1, it is easily removed after the envelop is cut at score 16, allowing the sheet to open without difficulty.

What I claim is:

1. A letter sheet having a window in the 70 upper part thereof, a seal flap integral with said sheet and adapted to have an address written thereon, and side flaps shaped to clear said window when folded, said seal flap when folded being arranged to lie on the folded side flaps, said window being arranged so that the address on the folded seal flap is visible therethrough when said sheet is folded into an envelop.

2. In a combined letter sheet and envelop, 80 a seal flap adapted to have an address written thereon, side flaps and an extended bottom flap having a window in the upper end thereof, said window being arranged so that the address on the seal flap is visible 85 therethrough when said sheet is folded into an envelop, said bottom flap being arranged to be folded to a line below said window and adapted to be held under said side and seal flaps, said seal flap being arranged when 90 folded to lie on said side flaps.

3. A letter sheet having a window in the upper end thereof, a seal flap integral with said sheet, side flaps shaped to clear said window when folded, scores on which said 95 sheet may be folded longitudinally into narrow strips of uniform width and transversely up under said side flaps to a line below said window to be held by said side flaps and seal flap to form an envelop, and a 100 transparent patch gummed to said sheet over said window.

4. A letter sheet adapted to be folded into an envelop, comprising a gummed seal flap, side flaps, and an extended bottom flap 105 arranged to be folded transversely several times along predetermined lines, longitudinal scores on which said flaps together with predetermined narrow longitudinal portions of said bottom flap of uniform width may be 110 folded after being folded transversely, and a transverse score on which said seal flap may be folded to form an envelop from said sheet, whereby said seal flap when folded rests on and is attached to said side and 115 bottom flaps.

Signed at the city of New York, in the county of New York and State of New York, this 23rd day of February A. D. 1918.

SAMUEL BROD.
